US00D463546S

(12) **United States Design Patent** (10) Patent No.: **US D463,546 S**
 Jansen et al. (45) Date of Patent: ** Sep. 24, 2002

(54) **DRUG CONTAINER HOLDER**

(75) Inventors: **Hubert Jansen, Poisat (FR); Lionel Vedrine, Saint Martin d'Heres (FR); Eric Denis, Caluire et Cuire (FR); Samuel Bernier, Caluire et Cuire (FR); Emmanuel Delarue, Sainte Foy les Lyon (FR)**

(73) Assignee: **Becton Dickinson and Company, Franklin Lakes, NJ (US)**

(**) Term: **14 Years**

(21) Appl. No.: **29/121,335**

(22) Filed: **Apr. 5, 2000**

Related U.S. Application Data

(63) Continuation-in-part of application No. 29/112,339, filed on Oct. 14, 1999, now Pat. No. Des. 446,578.

Primary Examiner—Ian Simmons

(74) *Attorney, Agent, or Firm*—Allen W. Wark, Esq.

CLAIM

The ornamental design for a drug container holder, as shown and described.

DESCRIPTION

FIG. 1 is a top, side and distal end perspective view of a drug container holder showing our new design;

FIG. 2 is a distal end view;

FIG. 3 is a proximal end view;

FIG. 4 is a top plan view having a bottom plan view being a mirror image; and,

FIG. 5 is a left side elevational view having a right side view being a mirror image.

1 Claim, 2 Drawing Sheets
